UNITED STATES PATENT OFFICE.

MICHAEL WILLIAM QUIRK, OF MILWAUKEE, WISCONSIN.

SHIPPING BOX OR CASE.

Application filed March 27, 1922. Serial No. 547,152.

To all whom it may concern:

Be it known that I, MICHAEL WILLIAM QUIRK, a citizen of the United States, and resident of Milwaukee, in the county of Milwaukee and State of Wisconsin, have invented new and useful Improvements in Shipping Boxes or Cases, of which the following is a description, reference being had to the accompanying drawings, which are a part of this specification.

This invention relates to improvements in shipping boxes or cases and particularly to containers of this type designed specially for holding bottles.

The invention has for one of its objects to provide means for reinforcing the lower portion of the box and furthermore to provide a construction whereby the lower section or bottom of the box when damaged or worn out may be quickly and conveniently replaced.

In shipping cases of this general type it has been found that the bottom of the box frequently becomes broken, because of the rough usage and strain to which it is subjected when the bottles are carelessly placed therein. Shipping cases therefore which are in every other respect suitable for continued use must be discarded, thereby incurring considerable expense in replacing the broken cases.

Therefore, as stated hereinbefore, the main object of my invention is to substantially reinforce the bottom of shipping cases or boxes and furthermore to so construct the same that the bottom may be made separable and may when the occasion demands be replaced.

In addition to this, this invention contemplates the reinforcement of the box proper as also the bottom thereof so that the whole container may more efficiently withstand the strain to which it is subjected during use.

The details of construction of this invention as well as the advantages incident thereto will be more completely set forth in the accompanying specification and shown in detail in the drawings, in which:—

Figure 1 is a side elevation of a shipping box or case constructed in accordance with this present invention,

Fig. 2 is an end elevation thereof,

Fig. 3 is a section taken on line 3—3 of Fig. 1,

Fig. 4 is a fragmentary detail view, taken on line 4—4 of Fig. 1,

Fig. 5 is a similar view of a modified form of construction, and

Fig. 6 is a similar view of still another modification.

In the drawings, reference being had to Figs. 1 to 4 particularly, it will be seen that the box or case consists of a four sided body 10 provided with a plurality of transverse rods 11 and longitudinal rods 12, which co-operate to serve as spacing means for dividing the box into compartments for receiving the individual bottles. In order to insure a firm connection between the box and the ends of the rods 11 and 12, each rod is provided with washers 13, which bear against the sides of the box 10.

In the form of this invention illustrated in Figs. 1 to 4 the bottom is shown as formed integrally with the box and the edge is recessed as at 14 to receive metal reinforcing strips or bands 15 secured in place by any suitable means, for instance, as shown herein by rivets 16.

The lower edge of the box 10 is provided with a centrally disposed metal strip 17, the ends of which are bent at right angles as indicated at 18 and secured in place by rivets 19 passing through these angularly bent ends and also through the reinforcing strips 15. In order to form a bottom or support for the contents of the box or case there is provided a plurality of longitudinally disposed rods 20 and transversely disposed rods 21, the ends of which pass through the lower edge of the box and through the reinforcing strips 15 and are formed with rivet-heads to firmly bind the lower edge of the box together. The transverse strip 17 is apertured at suitably spaced points to permit the longitudinal rods 20 to pass therethrough, thereby holding said longitudinal rods in spaced relation medially of their length.

From the structure described thus far it will be evident that a case or box is provided which is substantially reinforced throughout but particularly at its bottom which as mentioned hereinbefore is the inherently weakest part of this type of container.

In Fig. 5 the box 10 is shown as provided with recesses 22 and 23 to accommodate an L-shaped reinforcing strip 24 which, as in the case of reinforcing strip 15, may be secured to box by rivets or the like.

In Fig. 6 there is illustrated still another modification of this present invention in

which the bottom consists of a separate rectangular frame 25 recessed as at 26 to receive reinforcing strips 27, in the same manner as described with reference to the structure shown in Figs. 1 to 4. In this form the rectangular frame 25 would be provided with the transverse strip 17, the longitudinal rods 20 and the transverse rods 21, shown in detail in Fig. 3. The separate bottom 10 thus formed is in this instance secured to box 10 by means of nails, screws or the like 28 which pass upwardly through the rectangular frame 25 into the bottom edge of the box 10. Thus it is seen that a separate 15 and removable reinforced bottom is provided which when the occasion demands may be quickly and conveniently replaced.

While there is disclosed in some detail the several parts of this present invention 20 it should be understood that such disclosure does not limit the scope of the invention but that reservation is made to make such changes in the form thereof as may come within the purview of the accompanying 25 claims.

Having thus described the invention, what is claimed is:

1. In a shipping box or case, a body, the bottom edge of said body being formed with recesses, reinforcing strips disposed in said recesses and secured to said body and supporting rods extending across the bottom of said body and having their ends secured in said reinforcing strips.
2. A shipping box comprising a body, the bottom edge of said body being formed with

a recess, metal reinforcing strips disposed in said recess and secured to said body, an apertured strip secured to the bottom edge of said body and supporting rods extending across the bottom of said body and passing through the openings formed in said strip, the end of said rods being secured in said reinforcing strips.

3. In a shipping case or box, a body, spacing rods extending across said body and a removable bottom secured to said body, said bottom comprising a frame formed with a recess, reinforcing strips secured thereto and in said recesses and a plurality of transversely and longitudinally disposed rods, the ends of said rods being secured in said reinforcing strips.

4. In a shipping box or case, a rectangular body, partitioning rods extending across said body, washers carried by said rods and bearing against said body and a bottom removably secured to said body, said bottom comprising a rectangular frame formed with a recess, reinforcing strips disposed in said recess and secured to said frame, a transversely disposed metal strip secured to said frame and a plurality of longitudinally and transversely disposed rods extending across said frame, the ends of said rods being secured to said reinforcing strips, said metal strip being suitably apertured to permit said longitudinally disposed rods to pass therethrough.

In testimony whereof, I affix my signature.

MICHAEL WILLIAM QUIRK.
